ASSIGNORS TO KELLOGG SWITCHBOARD AND SUPPLY COMPANY, OF CHICAGO,
ILLINOIS, A CORPORATION OF ILLINOIS.

TELEPHONE SYSTEM.

Application filed April 29, 1921, Serial No. 465,392. Renewed March 23, 1925.

Our invention relates to multi-office telephone systems, that is, systems in which two or more exchanges are interconnected by means of trunk lines and in which trunking calls between exchanges are handled over these wires by operators in the originating exchange who pass the calls to operators in the distant exchanges, which latter complete the connections to the called subscriber's lines.

In systems of the trunking type which are in present use, A operators are provided who, by means of order wires, communicate with B operators at the distant exchanges, transmitting to them the numbers of the wanted lines, and the B operators then in turn designate to the A operators the trunks to be used. The A operator will then insert the calling plug of a pair into the designated trunk jack, while the B operator plugs into the called line. In the system embodying our invention, we provide the A operator with a plurality of local cords and in addition we equip her position with a number of outgoing and incoming trunk jacks and plugs for establishing trunk connections. The A operator reaches the B operator at the distant exchange by inserting the calling plug of a cord pair into a trunk jack, and automatic selection by means of switch mechanism then extends the call to an operator in the distant exchange who is idle. The system of our invention permits us to do away with B operators, in that all the operators in our system put up local calls which are completed in their own exchange, and also serve as trunk operators in that they receive calls transferred from distant exchanges and complete the connections required for such calls.

A feature of our invention is this, that when a trunking call has been completed from a calling subscriber in one exchange to the line of a called subscriber in a distant exchange, the interoffice trunk is released and immediately rendered available for use upon the conclusion of conversation and as soon as the calling subscriber replaces his

receiver, irrespective of the replacement of the receiver at the called substation. This immediate release permits a greater number of trunking calls to be handled per trunk than in previous systems in which the trunks are freed by the operators themselves.

Other features of the invention, as well as the one above outlined, will be more fully hereinafter described in the following description.

A clearer understanding of our invention may be had by referring to the accompanying drawings, in which Fig. 1, which comprises parts 1, 2 and 3, illustrates diagrammatically the apparatus used in establishing an inter-office call between a calling and called subscriber, and in which Fig. 2 illustrates a modification.

Fig. 3, illustrates a trunk jack having a high resistance relay connected thereto; the remainder of the apparatus used in connection with this figure but not shown is the same as that shown in Fig. 1, part 2.

Referring now to Fig. 1, part 1, we have illustrated a subscriber's substation A connecting the exchange with a line circuit L comprising the usual line relay LR, cut-off relay CO, multiple jacks J and multiple line lamps LL. The cord circuit C, which may be used for establishing either local or trunking connections, comprises an answering plug AP and a calling plug CP, the two plugs being connected by the heavily marked talking conductors. The cord circuit C comprises the usual answering and calling supervisory relays, answering and calling supervisory signals and the necessary relay apparatus for providing the various features necessary in a modern manually operated telephone switchboard, such as automatic ringing, automatic listening, secret service, automatic disconnect, line lamp recall, etc.

The apparatus for transferring trunking calls from one exchange to another includes a plurality of trunk jacks TJ at each operator's position, which terminates in multiple contacts located in banks of a plurality

of finder switches as FS located at the exchange at which the call originates, and one of these switches will automatically select the jack TJ in which an operator has inserted a calling plug CP of a cord circuit as C. The insertion of a plug CP into a trunk jack TJ starts the travel of a switch as FS, and when the switch has completed its operation of selecting the jack TJ into which a plug CP has been inserted, means are actuated to start the travel of a finder switch FS' at the distant exchange to select a trunk circuit E as illustrated in Fig. 1, part 3.

The trunk circuit E at its incoming end terminates in a repeating coil RC, and at its outgoing end is provided with a trunk plug TP for extending the call to a called subscriber. The trunk circuit E is provided with suitable apparatus for testing, ringing and supervision and the usual means for signaling back to the operator at the originating exchange.

Having described in general the apparatus embodying our invention we will now describe more in detail the operation of the circuit illustrated in Fig. 1, parts 1, 2 and 3, and Fig. 2.

Assuming now that a subscriber A at the exchange B desires to converse with a subscriber at the substation F in the exchange M, the subscriber at A initiating the call removes his receiver from its switchhook to close the switchhook contacts, which establishes an energizing circuit for the line relay LR of the line circuit L. Line relay LR upon energization closes its alternate contact, thus establishing a circuit for the multiple line lamps LL, which lamps are distributed at the various positions in the switchboard. An operator seeing a lamp LL at her position displayed, will insert the answering plug AP into the jack J of the calling line to close an energizing circuit for the sleeve relay SL from battery through the windings of the relay SL, normal contact 2 of the line relay LD, sleeve contacts of the connected plug AP and jack J and through the winding of the cut-off relay CO of line circuit L, to ground. The cut-off relay CO is energized over this circuit and opens the energizing circuit of the line relay LR to efface the multiple line lamps LL. The relay SL upon energization closes its alternate contact 3 and shunts out its high resistance upper winding so that if another operator has plugged into another jack of the line A, the sleeve relay SL of the second cord that has been plugged into a jack of the calling line will fail to energize because of the shunt established by the low resistance lower winding of the first sleeve relay SL, and the second operator not receiving a response when she asks for the number will withdraw her plug.

The relay SL of the first cord upon ener-

gization closes its alternate contact 4, establishing an energizing circuit for the listening relay LS, by current flowing from battery through the winding of the relay LS, alternate contact 4 of the relay SL, to ground at normal contact 5 of the sleeve relay SL'. Relay LS upon energization closes its alternate contacts 6 and 7 to connect the operator's set O to the calling line, and she now inquires the want of the calling subscriber at the substation A and learns that the subscriber F at the distant exchange is wanted. The closing of alternate contact 8 of the relay SL places the supervisory relay SR across the tip and sleeve conductors of the cord circuit C. The circuit of said relay SR being traced from battery through the lower winding of the relay SR, normal contact 9 of the relay LD, ring contacts of the connected plug AP and jack J, through the closed switchhook contacts at the substation A, back through the tip contacts of the connected plug AP and jack J, normal contact 10 of relay LD, alternate contact 8 of relay SL, through the upper winding of the relay SR, to ground. The relay SR upon energization opens its normal contact 14, preventing the display of the supervisory signal SS at this time. The closing of alternate contact 15 of relay SR establishes an energizing circuit for the meter relay MR, from battery through the winding of the meter relay MR, alternate contact 15 of the relay SR to ground at normal contact 16 of the relay 17. The closing of alternate contact 18 of relay MR closes an energizing circuit for the meter magnet MM from battery through the winding of the meter magnet MM to ground at alternate contact 18 of relay MR, which magnet MM upon energization actuates the counter mechanism to register a call as answered by the operator associated with the cord circuit C. The operator of the cord circuit C at the exchange B, learning that the line of the wanted subscriber terminates at the exchange M, will now insert the calling plug CP into the trunk jack TJ (such trunk jack TJ being assigned for calls to be extended to the exchange M) to start the operation of the finder switch FS to select the trunk jack TJ, as will now be described. The operator, however, before inserting the plug CP, actuates her cut-out key OK to close its alternate contacts 19 and 20. The insertion of the plug CP into the trunk jack TJ establishes an energizing circuit for the sleeve relay SL', the relay 17 and the relay 21, the circuit of relay 17 being traced from battery through the winding of the relay 17, conductor 22, normal contact 23 of the relay LD, conductor 24, through the winding of the relay 21, conductor 25, through the sleeve contacts of the connected plug CP and trunk jack TJ, to ground through

the winding of the trunk relay TR. The sleeve relay SL' has its energizing circuit closed from battery through the winding of the said relay SL', conductors 26 and 24, 5 through the winding of the relay 21, conductor 25, to ground through the relay TR, as above described. The energizing circuits of relays 17 and SL' are in parallel and said relays SL', 17 and 21 are energized 10 over the circuits just described due to the low resistance of the trunk relay TR. The relay SL' upon energization opens its alternate contact 5, opening the energizing circuit of listening relay LS, and the opening 15 of alternate contacts 6 and 7 disconnects the operator's set from the cord conductors. The opening of alternate contact 259 releases the busy relay BU common to her position, as will be more fully hereinafter described. Relay TR also energizes over the circuit just traced and upon energization closes its alternate contact 28, establishing an energizing circuit traced from ground through alternate contact 28, normal contact 23 of the relay 30, the common starting conductor SW, normal contact 30' of the switching relay SH, normal contact 31 of the off-normal contacts ON, normal contact 32 of the rotary magnet RM, through 30 the winding of the magnet RM to battery and ground. The rotary magnet RM will energize and de-energize, stepping the wipers 33, 34, 35 and 36 a first step from normal into engagement with the first set of contacts 37, 38, 39 and 40 in search of terminals of the trunk jack TJ in which the plug CP has been inserted. On the first step of the wipers off normal, the off-normal contacts ON are shifted to their alternate 40 positions, and successive actuations of the motor magnet RM are produced over a circuit traced from battery through the winding of the motor magnet RM, its contact 32, alternate contact 31 of the off-normal contacts ON, normal contact 41 of the switching relay SH to ground at normal contact 42 of the bridging relay BG. Such actuations will continue each energization and de-energization of the motor magnet RM, stepping the wipers 33, 34, 35 and 36 into engagement with successive contacts 37, 38, 39 and 40 until they engage multiple contacts in their banks connected to the trunk jack TJ into which the calling plug CP has been placed. As soon as the wiper 45 engages the contact 37 associated with the trunk jack TJ, an energizing circuit is established for the bridging relay BG, traced from battery through the associated resistance, through the upper winding of the relay BG, normal contact 43 of the relay BG, normal contact 44 of relay SH, wiper 33, engaged contact 37, normal contact 44' of the relay 30, to ground at alternate contact 45 of the relay TR. The relay BG upon 50 energization opens its normal contact 42, preventing further energizations of the rotary magnet RM (said magnet having already been shunted out by the upper winding of BG), and the closing of its alternate contact 46 establishes an energizing circuit for the relay 30 traced from battery, through the upper winding of the relay BG, its alternate contact 46, through the lower winding of the relay BG, wiper 34, contact 55 38, through the winding of the relay 30, to ground at alternate contact 47 of the relay TR. The relay 30 energizes over this circuit and opens its contact 44' so that no other switch whose wiper 33 engages the 60 multiple of the seized contact will stop, while the opening of normal contact 29 of the relay 30 keeps ground off the starting wire SW so that when the relay SH operates, which relay will energize due to the closure of alternate contact 42 of relay BG, it closes its alternate contact 30' to extend the starting wire SW to the starting wire SW', which extends to another finder switch in the usual manner, which latter finder 65 switch will be actuated in a similar manner, as above described when a plug is inserted into a trunk jack TJ. The relay SH having energized as above described closes a locking circuit for itself traced from battery through the winding of the relay SH, its alternate contact 48, to ground at alternate contact 49 of the off-normal contacts ON. The opening of normal contact 41 of relay SH and the opening of normal contact 42 of relay BG open the circuit of the motor magnet RM and prevent further actuation of the same. The relay BG upon 70 energization also closes its alternate contacts 50 and 51, establishing an energizing circuit for the relay 52 of the finder switch FS' at the distant exchange, said relay 52 having its windings connected across trunk conductors 53 and 54, and current now flows from battery through the upper winding 75 of relay 52, normal contact 55 of the relay 56, trunk conductor 53, alternate contact 50 of relay BG, wiper 35, contact 39, the tip contacts of the connected trunk jack TJ and plug CP, alternate contact 19 of the key OK, and through the left-hand winding of the relay 57 to ground, while another circuit is established from ground through the lower winding of the relay 52, normal contact 58 of the relay 56, alternate contact 51, wiper 36, contact 40, ring contacts of the connected jack TJ and plug CP, alternate contact 20 of the key OK, through the right-hand winding of relay 57 to battery and ground; it being remembered that at the 80 time the operator at the exchange B inserted the plug CP into the trunk jack TJ she actuated the cut-out key OK. Relays 52 and 57 are both energized over the circuits just described, and it is to be under- 85 90 95 100 105 110 115 120 125 130

stood that the relay 57 is common to all cords in an operator's position.

When the operator first actuated the cut-out key OK, the closure of alternate contact 258 of the key OK established an energizing circuit for the relay 59, traced from battery through the winding of the relay 59, to ground at alternate contact 258 of the key OK. The closure of alternate contact 60 of the relay 59 connects the special tone ST' through to the operator's set, via normal contact 61 of the relay 57, over conductor 62, through the tertiary winding 63 of the operator's set O to ground, and the operator thus has an audible indication which continues while the finder switch FS located at the exchange B is functioning in seeking an idle operator at the distant exchange M, and upon the energization of the relay 52 at the distant exchange the relay 57 upon energization over the circuit just described opens its normal contact 61, interrupting the special tone ST'. This interruption to the signal indicates to her that the finder switch FS has properly performed its function and has extended the call over the trunk conductors 53 and 54 to the distant exchange M, and that the finder switch FS' at the distant exchange has started its travel.

The relay 52 upon energization closes its alternate contact 65, establishing an energizing circuit for the rotary magnet RM', traced from battery through the winding of the rotary magnet RM', normal contact 66 of relay 67, normal contact 68 of off-normal contacts ON', to ground at alternate contact 65 of the relay 52, and upon energization the rotary magnet RM', through suitable pawl and ratchet mechanism, steps the wipers 69, 70 and 71 into engagement with the first set of contacts 72, 73 and 74 leading to a trunk circuit such as shown at E at the exchange M. Upon the first step of the wipers off-normal contacts ON' are shifted to their alternate positions, and if the contact 72 now engaged by the wiper 69 is a busy contact, it will be grounded, and the manner of such grounding will now be explained.

In case the first contact 72 connected by the wipers 69 is a grounded contact, circuit will be established from battery through the winding of the relay 67, alternate contact 75 of the rotary magnet RM', normal contact 76 of the relay 77, normal contact 78 of relay 56, through the winding of relay 79 to the ground at contact 72 engaged by wiper 69. Relays 67 and 79 energize over this circuit, the relay 79 being slow to release for purposes as will be presently described. The opening of normal contact 66 of the relay 67 opens the energizing circuit of the rotary magnet RM', and the rotary magnet RM' de-energizing opens its alternate contact 75, and the opening of the said contact 75 opens

the energizing circuit of the relay 67, and the closing of the normal contact 66 of the relay 67, due to its de-energization, will immediately re-establish an energizing circuit for the rotary magnet RM', which is again energized by current through the now closed contact 66, alternate contact 68 of the off-normal contacts ON', normal contact 76, normal contact 78, through the winding of the relay 79, to ground at the engaged contact 72, whereupon the rotary magnet RM' steps the wipers another step, and by the closure of its contact 75 will again energize the relay 67 over the previously described circuit to the wipers 69 and to the next engaged contact, if it is busy. Thus, a seesaw action between relay 67 and motor magnet RM' is produced, the slow relay 79 being in the circuit over which either one or the other is energized, and this seesaw action will continue until the wiper 69 engages a contact in its bank which leads to a trunk line in the exchange M which terminates before an operator who is not busy—that is, who is not busy establishing other trunk or local connections. When the wiper 69 engages an idle, i. e., ungrounded, contact 72, no energizing circuit is established through the slow release relay 79, and the relay 79 upon de-energization closes its normal contact 80, establishing an energizing circuit for the relay 56, traced from battery through the winding of the relay 56, normal contact 81 of relay 77, normal contact 80 of relay 79, to ground at alternate contact 82 of off-normal contacts ON'. The relay 56 upon energization closes its alternate contact 83 to establish an energizing circuit for the relay 77 traced from battery through the winding of the relay 77, alternate contact 83 of the relay 56, to ground at alternate contact 82 of the off-normal contacts ON'; and the relay 77 upon energizing immediately establishes a locking circuit for itself traced from battery through the winding of the circuit 77, its alternate contact 84 to ground at alternate contact 82 of the off-normal contacts ON'. The relay 77 upon energizing opens its normal contact 81, opening the initial energizing circuit for relay 56, but a substitute circuit will be established for it, as will presently be described. The relay 56 upon the closure of its alternate contacts 55 and 58 closes an energizing circuit for the relay 85 of the trunk circuit E at the exchange M, traced from battery through the right-hand winding of the relay 57 at the exchange B, alternate contact 20 of the key OK, ring contacts of the connected plug CP and trunk jack TJ, contact 40, wiper 36, alternate contact 51, the trunk conductor 54, alternate contact 58, wiper 71, engaged contact 74, winding a of the repeating coil RC, conductor 102, normal contact 103 of relay 104, conductors 105 and 106, through the lower winding of the relay 130

85, conductor 306, through winding *b* of the repeating coil RC, contact 73, wiper 70, alternate contact 55, trunk conductor 53, alternate contact 50, wiper 35, engaged contact 5 39, the tip contacts of the trunk jack TJ and plug CP, alternate contact 19, through the left-hand winding of the relay 57 to ground. The relay 85 of trunk circuit E is energized over this circuit, and the closure 10 of alternate contact 86 of the relay 85 closes an energizing circuit for the relay 87 from battery through the winding of the relay 87, to grounded alternate contact 86 of relay 85, and the closure of alternate contact 88 of 15 relay 87 extends ground to the contact 72 engaged by the wiper 69, busying the said contact 72, this ground also extending through the winding of relay 79 through alternate contact 78 of the relay 56, through 20 the winding of the said relay to battery and ground.

The circuit just traced is a substitute energizing circuit which is now established for the relay 56, the relay 56 having been momentarily held energized, due to its slow-to-release construction.

The relay 77 upon energization opened its normal contact 76 to prevent any further operations of the rotary magnet RM' until the relay 77 is again de-energized, which can only happen after the switch FS' is restored to normal and the contacts ON' are shifted to their normal position.

The relay 87 of the trunk E at the exchange M upon energizing as previously described, closes its alternate contact 89, establishing an energizing circuit for the relay 90 from battery through the winding of relay 90, to ground at alternate contact 89. The closure of alternate contact 89 also establishes an energizing circuit for the busying relay BU, traced from battery through the winding of the said relay BU, normal contact 91 of the sleeve relay SL² to ground at alternate contact 89 of the relay 87. The closure of alternate contacts 116, 117 and 118 of the busy relay BU places a ground on the conductors 119, 120 and 121 which lead to other trunks which terminate at the position, placing a busy potential upon the test contacts 72 of the trunk switches to which the trunks are multipled, preventing said trunks from being selected during the time that the operator is extending the connection to the called subscriber at the substation F. We also show a busy relay BU', which relay is common to an operator's position and is energized when an operator is establishing a local connection. When the cord circuit as B is used, the listening relay LS of the cord closes its alternate contact 259, which establishes an energizing circuit for the relay BU' from ground at alternate contact 259 of the listening relay LS of the cord that is used in establishing a local connection, to battery and ground through the winding of relay BU'. The closure of alternate contacts 260, 261, 262 and 263 connects ground to the trunk circuits terminating at this operator's position, the ground extending to the test contacts 72 of the switches FS' to which the trunks are multipled, preventing said switches from seizing any trunk terminating at her position while she is establishing a local connection. The closure of alternate contacts 92 and 93 of the relay BU connects the operator's relay OR to the trunk conductors, and the said relay OR energizes by current through both windings of the relay 57 at the exchange B over a path which is obvious from the previous description. The relay OR upon energizing closes its alternate contacts 94 and 95 to connect the operator's set O' of the trunk circuit E in circuit with the operator's set O at the exchange B, through alternate contacts 96, 97 of the relay 59, and the operator at the exchange B being now connected to the operator at the exchange M informs the operator at the exchange M of the number of the subscriber wanted, which we have assumed is the subscriber F, and the operator at the exchange M now inserts the calling plug of the trunk plug TP of the trunk circuit E into the jack J' of the wanted line, the operator having, of course, first tested the called line as to its idle or busy condition.

The closure of alternate contact 98 of the relay 87 establishes an energizing circuit for the indicating signal lamp IN, traced from battery through the lamp IN, normal contact 99 of the busy guard relay GU, to ground at alternate contact 98 of the relay 87. The lamp IN lighting informs the operator associated with a trunk E that a call has been extended to her position and indicates to her which of her trunk circuits is to be used in establishing the connection. After the operator at the exchange B has repeated the number of the called subscriber to the operator at the exchange M, she restores the cut-out key OK to its normal position, and the opening of alternate contact 258 of the key OK opens the circuit of the relay 59, which relay upon restoration opens its alternate contacts 96 and 97 to disconnect the operator's set O.

The closure of the make-before-break contacts 19 and 20 of the key OK establishes an energizing circuit for the supervisory relay SR' of the cord circuit C at the exchange B, traced from battery through the lower winding of the relay SR', alternate contact 100 of the relay 17, normal contact 101 of the ringing interrupter relay RI, normal contact 20 of the key OK, ring contacts of the connected plug CP and trunk jack TJ, and over the trunk conductor through the winding *a* of the repeating coil RC, conductor 102, normal contact 103 of the relay

104, conductors 105 and 106, through the lower winding of the relay 85, conductor 306, through the winding *b* of the repeating coil RC, returning over the trunk conductor 5 through the tip contacts of the connected plug CP and trunk jack TJ, normal contact 19 of the key OK, normal contact 107 of the relay RI, alternate contact 108 of the relay 17, through the upper winding of the relay SR', conductor 109 to ground at alternate contact 110 of the relay 17. The relay SR' energizes over this circuit and the opening of its normal contact 111 opens the circuit of the supervisory signal SS' which was 15 illuminated as a result of the energization of relay SL' upon the insertion of plug CP into jack TJ, and thus provides dark keyshelf operation for the cord circuit C at the exchange B. By "dark keyshelf" is meant 20 that there is no signal displayed in connection with the operator's cord after she has once completed the manual operations such as inserting the plugs and operating the keys, etc., necessary in doing work in putting 25 up a connection.

Having assumed that the line of the subscriber F is idle and that the operator inserts the trunk plug TP into the jack J' of the called line, this insertion establishes a 30 series energizing circuit for the sleeve relay SL² and cut-off relay CO² of the called line circuit L', traced from battery through the winding of the relay SL², sleeve contacts of the connected plug TP and jack J' to ground 35 through the cut-off relay CO². The sleeve relay SL² upon energization closes its alternate contact 112, establishing an energizing circuit for the busy guard relay GU, traced from battery through the upper winding of 40 the relay GU, its normal contact 113, alternate contact 114 of the relay 87, to ground at alternate contact 112 of the relay SL². A locking circuit is closed through the lower winding of the relay GU traced from battery 45 through the winding of relay GU, alternate contact 99, to ground at alternate contact 98 of the relay 87. The opening of normal contact 99 effaces the indicating signal IN. A locking circuit is also established 50 through the upper winding of the relay GU, traced from battery through its alternate contact 115, to ground at alternate contact 112 of the relay SL². These two locking circuits of the relay GU as just traced are 55 for purposes as will be presently described.

The opening of normal contact 91 of the sleeve relay SL² opens the energizing circuit of the busy relay BU, which relay opens its alternate contacts 116, 117 and 118 to remove 60 ground from the conductors 119, 120 and 121, which conductors lead to the multiple test contacts 72 of the trunk switches FS', rendering the remaining trunks at her position selectable, as the operator has extended 65 connection to the called subscriber and is now

free to receive other trunk connections, providing she is not now engaged in establishing local connections, and if she is thus occupied the trunks are rendered busy in the manner as previously described.

The closure of alternate contact 122 of the relay GU establishes an energizing circuit for the meter magnet MR', traced from battery through the winding of the meter magnet MR', normal contact 123 of the meter cut-off relay MO, to ground at alternate contact 122, and the meter magnet MR' is now actuated to register a connection. The closing of alternate contact 122 also establishes a circuit from the meter cut-off relay MO, traced from battery through the winding of the relay MO to ground at alternate contact 122, and the meter cut-off relay MO energizing opens its normal contact 123, preventing further actuations of the meter magnet MR', which meter magnet MR' now restores to normal.

A circuit for the ringing lamp RL is also established, traced from battery through the lamp RL, normal contact 124 of the ringing control relay RC', normal contact 125 of the ringing trip relay RT', normal contact 126 of the relay 104, to ground at alternate contact 112 of the relay SL². The ringing lamp RL is lighted over this circuit and gives the operator of the trunk circuit E a visual indication that the called subscriber at the substation F has not as yet been signaled. To signal the called-for subscriber at the substation F, the operator associated with the trunk circuit E now depresses the proper ringing key plunger of the ringing key RK' to connect the ringing generator of the proper frequency to operate the call signal of the called subscriber at the substation F. The depression of the ringing key plunger of the ringing key RK' associated with the selected frequency also brings about the actuation of the end spring contact 127 of the ringing key RK', causing it to momentarily assume its alternate position, and the closure of the said alternate contact 127 establishes an energizing circuit for the ringing control relay RC', traced from battery through the winding of the said relay RC', momentarily closed end spring contact 127, normal contact 126 of the relay 104, to ground at alternate contact 112 of the sleeve relay SL².

The closing of alternate contact 128 of relay RC' establishes a locking circuit for itself, traced from battery through the winding of said relay RC', through alternate contact 128, normal contact 125 of the ringing trip relay RT', contact 126 of relay 104, to ground at alternate contact 112 of the sleeve relay SL². Relay RC' upon energizing opens its normal contact 124, effacing the ringing signal lamp RL. The closing of alternate contact 130 of relay RC' estab-

lishes an energizing circuit for the ringing interrupter relay RI' , traced from battery through the winding of relay RI' , alternate contact 130 of the relay RC' , alternate contact 131 of the relay 87, through the constantly rotating interrupter I' to ground. The ringing interrupter relay RI' is thus intermittently energized and de-energized by the interrupter I' , and the ringing current from the selected generator frequency is thus connected and disconnected to intermittently operate the call signal of the called-for substation F.

The ringing current may be traced from the ungrounded pole of the selected generator, through the closed key plunger contact, through the winding of the ringing trip relay RT' , alternate contact 135 of relay RI' , tip contacts of the connected plug TP and jack J' , through the condenser and call bell of the called substation F, back through the ring contacts of the connected plug TP and jack J' , to battery and ground through alternate contact 136 of the ringing interrupter relay RI' . The call signal of the substation F is intermittently rung due to the intermittent energization and de-energization of the interrupter relay RI' , and the subscriber at the substation F in response to his call signal removes his receiver from the switchhook. Should the subscriber at the substation F remove his receiver during a ringing period, the combined generator and battery flow through the winding of the ringing trip relay RT' causes the same to actuate, and the opening of its normal contact 125 opens the locking circuit of the ringing control relay RC' , which relay RC' restores, and the opening of its alternate contact 130 disconnects the interrupter I' from the interrupter relay RI' ; the said relay RI' now remaining at normal and preventing further application of ringing current after the called subscriber at the substation F answers in response to his call signal.

Should the subscriber at the substation F remove his receiver during a silent period, that is, when the ringing interrupter relay RI' is in one of its de-energized positions, an energizing circuit for the supervisory relay SR^2 is established, said circuit being traced from battery through the lower winding of the relay SR^2 , the winding c of the repeating coil RC , normal contact 136 of the relay RI' , ring contacts of the connected plug TP and jack J' , through the now closed contacts of the substation switchhook, back through the tip contacts of the jack J' and plug TP, normal contact 135 of the relay RI' , alternate contact 137 of the sleeve relay SL^2 , the winding d of the repeating coil RC , to ground through the upper winding of the supervisory relay SR^2 . The supervisory relay SR^2 upon energiza-

tion closes its alternate contact 138, establishing an energizing circuit for the relay 104, traced from battery, through the winding of the said relay 104, alternate contact 138, to ground at alternate contact 112 of the sleeve relay SL^2 . The relay 104 upon energization closes its alternate contact 139, establishing a locking circuit for itself traced from battery through the winding of the said relay 104, its alternate contact 139, to ground at alternate contact 112 of the sleeve relay SL^2 . The relay 104 upon energization opens its normal contact 103, which opens the shunt circuit from about the upper high resistance winding of the relay 85, but due to the fact that the supervisory relay SR^2 upon energization closes its alternate contact 140, it provides another shunt about the upper high resistance winding of the relay 85, which may be traced from conductor 102, through alternate contact 140 of the relay SR^2 , conductor 106, through the lower low resistance winding of the relay 85 and over conductor 306, thus allowing the supervisory relay SR' of the cord circuit C at the exchange B to remain energized so that the lamp supervisory signal SS' in the cord circuit C in exchange B remains dark while the subscribers are talking.

The subscriber at the substation A at the exchange B and the subscriber at the substation F at the exchange M are now in conversational circuit, and the talking circuit may now be traced over the heavily marked conductors. The talking current for the substation A comes through the supervisory relay SR of the cord C at the exchange B and talking current is supplied to the called substation F from battery through the windings of the supervisory relay SR^2 of the trunk circuit E at the exchange M.

Assuming that the subscribers have finished conversation, they replace their receivers upon their respective switchhooks, and the replacing of the receiver by the subscriber at the called substation F brings about the de-energization of the supervisory relay SR^2 , and the relay opens its alternate contact 140. The opening of alternate contact 140, due to the de-energization of the supervisory relay SR^2 , removes the shunt from about the upper high resistance winding of the relay 85, since relay 104 is now in a locked position through its alternate contact 139, to ground at alternate contact 112, and current through the supervisory relay SR' of the cord circuit C at the exchange B now extends from battery through the lower winding of the relay SR' and over the heavily marked trunk conductor, through the winding a of the repeating coil RC , conductor 102, through the upper high resistance winding and lower low resistance winding of the relay 85, over conductor 306, through the winding b of the repeating coil 120

RC and over the heavily marked conductor, through the upper winding of the supervisory relay SR' to ground at alternate contact 110 of the relay 117. The relay SR' of cord C at exchange B, due to the high resistance winding of the relay 85 of the trunk circuit E at the exchange M, does not receive sufficient current to remain energized and, therefore, restores, and the closing of its normal contact 111 establishes a circuit for the supervisory signal SS', traced from battery, through the lamp SS', normal contact 145 of relay RC, normal contact 146 of the relay LD, normal contact 147 of the ringing trip relay RT, normal contact 111 of the relay SR', to ground at alternate contact 5 of the sleeve relay SL'.

The subscriber at the substation A replacing his receiver upon the switchhook 20 opens the energizing circuit of the supervisory relay SR, at the switchhook contacts. Relay SR now restores to normal, and the closing of its normal contact 14 establishes an energizing circuit for the link disconnect 25 relay LD, traced from battery through the winding of relay LD, normal contact 14, alternate contact 150 of the sleeve relay SL, to ground at alternate contact 5 of the sleeve relay SL'. Relay LD upon energizing 30 opens its normal contacts 9 and 10, disassociating the calling line from the strands of the cord circuit, and the opening of its normal contact 2 opens the circuit of the relay SL, but the relay SL has a substitute 35 energizing circuit established for it, traced through the alternate contact 2 of the relay LD to ground at alternate contact 5 of the sleeve relay SL'. The closing of normal contact 14 of relay SR also establishes 40 a circuit for the supervisory lamp SS, traced from battery through the lamp SS, normal contact 14, alternate contact 150, to ground at alternate contact 5 of the relay SL'. The opening of normal contact 45 23 of the relay LD opens the energizing circuit of the relay 17, and the said relay 17 upon de-energization opens its alternate contacts 100 and 108, thus interrupting the cord strands of the cord circuit C 50 from the connected trunk jack TJ. As soon as the relay 17 is cut off from the sleeves strands of the cord circuit C at the exchange B, due to the opening of normal contact 23 of the relay LD, there will be only one battery 55 connection remaining on the sleeve strand which may be traced from battery through the winding of the sleeve relay SL', through the winding of relay 21, over conductor 25, through the sleeve contacts of the 60 connected plug CP and trunk jack TJ, to ground through the winding of the relay TR. The relay SL' is of comparatively high resistance—for instance, from 7000 to 7500 ohms—and the current passing over 65 the circuit just traced is sufficient to main-

tain the relay SL' and the relay 21 energized; but the relay TR , owing to its relatively low resistance and the adjustment of its spring contacts, de-energizes, and its contacts 28, 45 and 47 restore to normal. The opening of alternate contact 47 opens the energizing circuit of the relay BG , which relay de-energizes, and in so doing its alternate contacts 50 and 51 are opened, opening the talking conductors extending through to wipers 35 and 36. 70 75

Upon the closing of normal contact 42 of relay BG, upon its de-energization an energizing circuit is established for the release magnet RR, which may be traced from battery through the winding of the release magnet RR, alternate contact 41 of the relay SH, to ground at normal contact 42 of the relay BG, which is now at normal, and the release magnet RR upon energizing withdraws the retaining pawl of the switch, and the wipers 33, 34, 35 and 36 are spring-
restored to normal. 80 85

The opening of contact 47 of relay TR, of course de-energizes the relay 30, and upon the wipers restoring to normal the off-normal contacts ON are moved to their normal position, and all the mechanism of the finder switch FS at the exchange B is now at normal. 95

Upon the opening of alternate contacts 50 and 51 of the relay BG, the relay 85 at the trunk circuit E at the exchange M has its circuit opened and consequently is de-energized. The opening of its contact 86 opens the energizing circuit of the relay 87, and the relay 87 upon de-energization opens its contact 89, which allows the relay 90 to de-energize. The opening of alternate contact 88 removes ground from the contacts 72 at the exchange E, and as the relay 90 is of a slow-to-release construction, it will keep its contact 160 in its alternate position long enough to insure that the relay 56 of the switch FS' will restore, and the relay 56 upon de-energization opens its alternate contacts 55 and 58, placing the wipers 70 and 71 on open circuit. The closing of normal contact 83 of the relay 56 closes an energizing circuit for the release magnet RR', traced from battery through the winding of the magnet RR', through alternate contact 161 of the relay 77, normal contact 83 of relay 56 to ground at the alternate contact 82 of the off-normal contacts ON'. The release magnet RR' upon energization withdraws the retaining pawl of the switch, and the wipers 69, 70 and 71 are spring-restored to normal, and when the wipers 69, 70 and 71 reach their normal position, the off-normal contacts ON' are moved to their normal positions, and the opening of contact 82 opens the locking circuit of the relay 77, which upon restoration opens its alternate contact 161, bringing about the de-energization of 130

the release magnet RR', and the mechanism of the finder switch FS' at the exchange E is at normal.

It is thus seen that when the two subscribers have finished conversation and have replaced their receivers, the two switches FS and FS' are released and fully restored so that they are immediately free, thus rendering the trunk line promptly available for another connection.

The operator at the exchange B, noting the signal lamps SS and SS' displayed, withdraws the plugs AP and CP, and the withdrawal of the plug CP from the trunk jack TJ brings about the de-energization of the sleeve relay SL' and the relay 21. The relay SL' upon de-energization opens the circuit of the link disconnect relay LD, and the relay LD upon de-energization opens its alternate contact 2 to open the energizing circuit of the sleeve relay SL. The apparatus of the cord circuit C at the exchange B is now at normal and available for use in establishing other connections.

25 The relay 87 at the trunk circuit E of the exchange M upon de-energization closes a circuit for the disconnect signal DS, traced from battery through the lamp DS, alternate contact 165 of relay SL², to ground at normal contact 98 of the relay 87, and the operator of the trunk circuit E at the exchange M observing the disconnect signal DS now withdraws the trunk plug TP from the jack J' of the subscriber's line, opening the series energizing circuit of the sleeve relay SL² and cut-off relay CO², and the opening of alternate contact 112 of the relay SL² permits the de-energization of the relay 104 and the relay GU. The apparatus at the trunk circuit E is now at normal and available for use in establishing other connections.

The calling subscriber at the substation A of exchange B upon replacing his receiver upon the switchhook, immediately disconnects his line from the connected cord circuit C due to the energization of the relay LD and thus places the line relay LR of the line circuit of the calling subscriber under his control, so that if he wishes to recall he may do so by again removing his receiver, even though the plug AP remains in the jack J, and his act of removing the receiver again brings about the energization of the line relay LR to light the multiple line lamps LL so that any one of a plurality of operators may seize the recall.

Assuming now that the calling subscriber is the first to replace his receiver upon the switchhook, the replacing of the receiver opens the energizing circuit of the supervisory relay SR at the switchhook contacts, and the closing of normal contact 14 establishes an energizing circuit for the link disconnect relay LD from battery through the

winding of relay LD, normal contact 14, alternate contact 150 to ground at alternate contact 5 of the relay SL'. The closing of normal contact 14 also establishes an energizing circuit for the supervisory signal SS' to ground at alternate contact 5 of the sleeve relay SL'. The opening of normal contact 2 opens the initial energizing circuit for the sleeve relay SL, but a substitute circuit for the said relay SL is established, as previously described, to ground at alternate contact 5 of the relay SL'. The opening of normal contact 23 of the relay LD opens the energizing circuit of the relay 17, and the relay 17 upon restoration opens its alternate contacts 100 and 108, disconnecting the cord conductors from the connected trunk jack TJ. The sleeve relay SL' and the relay 21 are the only relays now connected to the sleeve conductor of the cord C, and due to the high resistance of the sleeve relay SL', as before described, the relay TR of the trunk jack TJ does not receive sufficient current and, therefore, restores to normal.

The relay TR upon de-energization opens its alternate contacts 28, 45 and 47, and the opening of alternate contact 47 opens the energizing circuit of the relay BG, which relay de-energizes, and in so doing its alternate contacts 50 and 51 are opened, opening the talking conductors extending through the wipers 35 and 36. The relay BG upon de-energization closes its normal contact 42, establishing an energizing circuit for the release magnet RR, which magnet RR withdraws the retaining pawl of the switch and permits the restoration of the wipers 33, 34, 35 and 36 to normal, as previously described. Upon the opening of alternate contacts 50 and 51 of the relay BG, the relay 85 of the trunk circuit E at the exchange M has its circuit opened and consequently de-energizes. The retraction of the alternate contact 86 of the relay 85 opens the energizing circuit of the relay 87, and the relay 87 upon de-energization opens its alternate contact 89, which allows the relay 90 to deenergize. The opening of alternate contact 88 removes the ground from the test contacts 72 of the switch FS' at the exchange M. The removal of this ground allows the relay 56 to restore, and the opening of alternate contacts 55 and 58 places the wipers 70 and 71 on open circuit, and the closing of normal contact 83 of the relay 56 closes an energizing circuit for the release relay RR', and the release magnet upon energizing withdraws the retaining pawl and allows the wipers to restore to normal, the off-normal contacts ON' also restoring.

The called subscriber at the substation F replacing his receiver opens the energizing circuit of the supervisory relay SR², and the restoration of the relay 87, due to the de-energization of the relay 85 closes a circuit

for the disconnect signal DS as previously described, and the operator noting the lighted disconnect signal DS, withdraws the trunk plug TP from the jack J', which withdrawal 5 allows the sleeve relay SL² to restore to normal, bringing about the effacement of the signal DS. The opening of alternate contact 112 of the relay SL² opens the locking circuit of the relay 104. The apparatus used 10 in establishing a connection between the calling subscriber at the substation A of the exchange B and the called subscriber at the substation F at the exchange M is now at normal and available for use in establishing 15 other connections.

From the previous description it may be seen that the calling subscriber of the substation A at all times controls the disconnection of the finder switch FS at the exchange 20 B, and the finder switch FS' at the exchange M.

In case the called subscriber at the substation F at the exchange M is being signaled and does not answer the call, the calling subscriber at A in replacing his receiver upon the switchhook will de-energize the supervisory relay SR in the cord circuit C, and the relay SR de-energizing closes the circuit through the link disconnect relay LD. 25 The relay 17 has its circuit opened at the contact 23 of the relay LD, and it is plain from the preceding description that the switch FS will restore, as does also the finder switch FS', and circuit being opened 30 through the wipers 70 and 71 of the switch FS', relay 85 of the trunk circuit E of the exchange M de-energizes, bringing about the restoration of the relay 87. The relay 87 upon restoration opens its alternate contact 35 131, interrupting circuit through the ringing interrupter relay RI', thus disconnecting ringing current from the called line. Ringing control relay RC' remains energized over the circuit hereinbefore traced to prevent the ringing lamp RL from burning. 40 The closing of normal contact 98 of relay 87 lights the disconnect signal DS, and the operator of the trunk E at the exchange M now withdraws the plug TP and the operator at 45 the exchange B receiving disconnect signals SS and SS', withdraws the plugs AP and CP from the respective jacks J and TJ, and the apparatus used in establishing this attempted connection is now at normal and 50 available for use in establishing other connections.

Assuming now that the calling subscriber at the substation A removes his receiver to 60 initiate a call for a subscriber in his own exchange, the operation of the line circuit L and the cord circuit C of Fig. 1, part 1, will be the same as that already described, until after the operator has received the number of the calling subscriber. In this 65 case she will test a multiple jack of a called

subscriber's line whose line circuit and substation will have exactly the same arrangement as that of the subscriber A. To make the test the operator touches the tip of the plug CP to the sleeve of the jack of the 70 called line. If the said called line is busy because the plug of another cord circuit has already been placed into a multiple of the jack to be tested (provided always a subscriber has not effected automatic disconnection), there will be a potential on the tested 75 sleeve contact of the jack, and an impulse of current will flow through the tip of the plug CP, normal contact 19, normal contacts 107 and 108, the closed contact 200 of the relay LS, and to ground through test relay T, which is common to an operator's position. The relay T upon energization will actuate to close its alternate contact 201 to close 80 battery through the tertiary winding 63 of the operator's induction coil, giving her the customary busy click.

We also provide testing means for giving the operator a revertive tone test if she is testing a multiple jack of a line in which 90 she has already inserted the answering plug of the cord, that is, if the calling subscriber at the substation A wants another subscriber on his own line; the system thus providing for a case in which there are a number of substations connected to a single line. In making such a revertive test the operator will receive the click as usual, but in addition the closure of alternate contact 202 of the relay T will connect the revertive tone test ST, the special tone circuit being traced from the tone device ST, alternate contact 202 of the relay T, alternate contact 203 of the relay LS, normal contact 2 of the relay LD, through the sleeve contact of the plug AP to the sleeve of the jack J into which that plug is inserted, thence to the sleeve of the jack that is being tested and over the tip of the calling plug CP, through normal contact 19 of the key OK, normal contacts 107 and 108, through alternate contact 200 of the relay LS, to ground through the tertiary winding 63 of the operator's induction coil. The operator hearing this special tone 105 will know it is a revertive call and tell the calling subscriber to momentarily replace his receiver, and the operator will then withdraw the plug AP, inserting the calling plug CP and ring in the usual manner.

Assuming that the called-for substation is on an idle line and entirely independent of that of the subscriber at the substation A, the operator receiving no click upon her test, inserts the calling plug CP into the non-busy jack, thus placing the sleeve relay SL' and the relay 17 of the cord circuit C in connection with the ground through the winding of the cut-off relay CO of the called line. The circuit of relay 17 and the circuit of relay SL' extend through the winding of 110 115 120 125 130

the relay 21, and due to the high resistance of the cut-off relay CO of the called line the relay 21 does not operate, but the relays SL' and 17 operate over the circuit just described. The operator associated with the cord circuit C now actuates one of the ringing key plungers of the ringing key RK connected with the ringing generator of the proper frequency to actuate the call bell at the called substation. The depression of her ringing key plunger of her ringing key RK momentarily closes the end spring contacts 204 and 205, and the closing of the ringing key end spring contact 205 closes an energizing circuit for the ringing control relay RC, traced from battery through the winding of the relay RC, momentarily closed end spring contact 205, normal contact 146 of the relay LD, normal contact 147 of the ringing trip relay RT, normal contact 111 of the supervisory relay SR' to ground at alternate contact 5 of the sleeve relay SL', and the closing of alternate contact 145 of the relay RC closes a locking circuit for itself from battery through the winding of the said relay RC, its alternate contact 145, through normal contact 146 of the relay LD and over the previously described path to ground at alternate contact 5 of the sleeve relay SL'. The momentary closure of the end spring contact 204 closes an energizing circuit for the ringing interrupter relay RI traced from battery, through the upper winding of the relay RI, closed end spring contact 204 to ground at alternate contact 206 of the ringing control relay RC, so that the called substation is instantly rung and will continue to be rung as long as the operator keeps the end springs 204 and 205 shifted, the ringing current extending from the generator through the depressed key plunger, through the lower winding of the relay RT, alternate contact 107 of the relay RI, and through the condenser and call bell at the called substation and back to battery and ground at alternate contact 101 of the relay RI.

When the operator releases the ringing key plunger, the end springs open their contacts 204 and 205, and as the relay RC has closed a locking circuit for itself, as described, the constantly rotating interrupter I is connected to the ringing interrupter relay RI, traced from battery through the lower winding of the relay RI, alternate contact 207 of the relay RC to ground through the constantly rotating interrupter I. The relay RI will be thus intermittently energized and de-energized to connect and disconnect ringing current through its alternate contact 107, ringing current being traced from the selected generator through the lower winding of the ringing trip relay RT, alternate contact 107 of the relay RI, normal contact 19 of the key OK, tip con-

tacts of the connected plug CP and jack of the called line, through the call bell and condenser at the called substation, the ring contacts of the connected jack and plug CP, normal contact 20 of the key OK to battery 70 and ground through alternate contact 101 of the relay RI.

Should the subscriber answer during a ringing period, the reduced resistance at the substation caused by the removal of the receiver allows sufficient current to flow through the lower winding of the relay RT to energize it, and the said relay RT upon energization opens its normal contact 147, opening the locking circuit of ringing control relay RC, and the said relay RC upon restoration opens its alternate contact 207, interrupting the circuit for the ringing interrupter relay RI, thus preventing further energizations and de-energizations of the relay RI and preventing further application of ringing current to the called line.

If the called subscriber removes his receiver during a silent period, the normal contacts 101 and 107 of the ringing interrupter relay RI will be closed and the supervisory relay SR' will immediately energize through the now closed contacts of the subscriber's switchhook, and the opening of normal contact 111 of the relay SR' will open the locking circuit of the ringing control relay RC to prevent further energizations and de-energizations of the ringing interrupter relay RI. The calling and called subscribers are now in conversational circuit, which may be traced over the heavily marked conductors.

Assuming now that the subscribers have finished conversation and that the called subscriber is the first to replace his receiver upon the switchhook, the opening of the switchhook contacts at the called substation opens the energizing circuit for the supervisory relay SR', and the closing of normal contact 111 of the supervisory relay SR' establishes a circuit for the supervisory signal SS' from battery through the said lamp, normal contact 145, normal contact 146 of relay LD, normal contact 147 of relay RT, normal contact 111 of relay SR', to ground 115 at alternate contact 5 of the sleeve relay SL'. The relay 17 does not de-energize at this time due to the fact that the calling subscriber has not as yet replaced his receiver upon the switchhook, and the replacing of the receiver at the called substation at this time does not disconnect said called line from the connected cord.

When the calling subscriber at the substation A replaces his receiver upon the switchhook, the opening of the switchhook contacts opens the energizing circuit of the supervisory relay SR, and the closing of normal contact 14 of the relay SR closes an energizing circuit for the link disconnect relay LD 120

from battery, through the relay LD to ground at alternate contact 5 of the sleeve relay SL'. The relay LD upon energization opens its normal contact 23, opening the energizing circuit of the relay 17, and the relay 17 de-energizing opens its alternate contacts 100 and 108, disconnecting the cord conductors from the line of the called subscriber, and the energization of the link 10 disconnect relay LD brings about the opening of its normal contacts 9 and 10, also disconnecting the answering end of the cord circuit from the line of the calling subscriber. Upon the de-energization of the relay 15 17, the sleeve relay SL' and the relay 21 are the only relays now connected to the sleeve strand of the cord and due to the high resistance of the sleeve relay SL' of the cord circuit C, the cut-off relay of the line circuit 20 of the called line does not receive sufficient current to hold it up and it restores to normal, again placing the line relay under the control of the called subscriber, so that the called subscriber may initiate a recall. Upon 25 the energization of the link disconnect relay LD of the answering end of the cord circuit C, the sleeve strand of the cord is opened at the normal contact 2 of the relay LD, thus permitting the cut-off relay of the 30 calling line to restore to normal and placing the line relay LR of the calling line under the control of the calling subscriber so that he may immediately recall upon the replacement of his receiver upon the switchhook. 35 Should the calling subscriber replace his receiver upon the switchhook first, the supervisory relay SR will restore to normal and the closing of its normal contact 14 energizes the link disconnect relay LD, and the link 40 disconnect relay LD energizing disconnects the line of the calling subscriber in the cord circuit, as before described.

The opening of the normal contact 23 of the link disconnect relay LD does not affect 45 the relay 17 at this time, due to the circuit through contact 240. Should the called subscriber not as yet have placed his receiver upon the switchhook, under these conditions the supervisory relay SR' is still maintained 50 energized over the called line, and the relay 17 will remain energized from battery through the winding of the relay 17, alternate contact 240 of the relay SR', normal contact 241 of the relay 21 (relay 21 not energizing when the cord circuit C is used for 55 establishing a local connection, due to the comparatively high resistance of the cut-off relay CO of the line circuit of the subscriber), through the winding of the relay 21, conductor 25, sleeve contacts of the connected plug CP and the jack of the called line, to the ground through the cut-off relay of the called line circuit.

Now, when the called subscriber replaces 60 65 his receiver on the switchhook, the supervi-

sory relay SR' restores and the opening of its alternate contact 240 opens the energizing circuit of the relay 17, and the relay 17 upon restoration opens its alternate contacts 100 and 108, and the operation of the circuit 70 from this point on is the same as previously described.

Referring now to Fig. 2, we illustrate a cord circuit C' similar to that of Fig. 1, part 1, and which may be substituted in place of Fig. 1, part 1, in connection with Fig. 1, parts 2 and 3. Corresponding relays and apparatus bear the corresponding reference characters, but with an exponent added. The operation of the circuit is similar to that of Fig. 1, part 1, and the calling end of the cord C' is adapted to operate in connection with a low-wound cut-off relay of the called line when establishing a local connection, and a high resistance trunk relay when operating in connection with a trunking connection. When the calling plug CP' of the cord C' is inserted in a local jack of a called line due to the low-wound cut-off relay, relays 17' and SL⁴ operate over a parallel circuit, the circuit of relay SL⁴ being traced from battery through the winding of relay SL⁴, conductors 275 and 276, the sleeve contacts of the plug CP' and jack of the called line, to ground through the cut-off relay of the called line, and the circuit of relay 17' being traced from battery through the winding of relay 17', conductor 277, normal contact 23' of relay LD', conductor 278, through the winding of relay 21', conductor 276, to ground through the cut-off relay of the called line. All three relays, namely, SL⁴, 21' and 17' operate over this circuit due to the low resistance of the cut-off relay. When the called subscriber answers, the supervisory relay SR⁴ operates and closes its alternate contact 279, and as contact 280 of relay 21' is closed due to its energization, relay 17' is placed under the control of the called subscriber. 90

When conversation terminates, should the calling subscriber at A' replace his receiver first, the link disconnect relay LD' will operate; as is obvious from the previous description, but the opening of contact 23' of relay LD' does not bring about the de-energization of relay 17' at this time, as the said relay is maintained energized through alternate contacts 279 and 280 of relays SR⁴ and 21' and through the winding of relay 21' to ground. 115 Now, when the called subscriber replaces his receiver, the supervisory relay SR⁴ restores, and the opening of its alternate contact 279 opens the energizing circuit of relay 17', and the relay 17' restores and disconnects the cord conductors. Relay SL⁴ is now the only relay connected to the sleeve strand and (due to its high resistance) the cut-off relay of the called line fails to remain energized, and it restores for purposes as previously de- 120 125 130

scribed in connection with Fig. 1, parts 1, 2 and 3. Should the called subscriber replace his receiver first, the relay SR⁴ restores, but relay 17' is maintained energized

5 through normal contact 23' of LD', and when the calling subscriber replaces his receiver relay LD' will energize to open the circuit of 17', and the operation of circuit from this point will be the same as already

10 described.

When a connection is extended over a trunk to a distant exchange, relay 21' will not operate due to the high resistance of the trunk relay TR' of the trunk circuit, as shown

15 in Fig. 3, so that the relay 17' will be solely under the control of the calling subscriber, as the contact 280 of relay 21' remains open due to its failure to operate, and as soon as

20 the calling party replaces his receiver relay LD' will operate to open its normal contact 23', thus allowing relay 17' to restore, and the operation of the circuit from this point on is the same as previously explained.

While we have illustrated and described a particular embodiment of our invention, it is to be understood that we do not intend to be limited to the particular structure which is herein described and illustrated, but intend to cover all such changes and modifications as come within the spirit and scope of the appended claims.

Having described our invention, what we claim as new and desire to secure by United States Letters Patent, is:

35 1. In a telephone system, an operator's cord circuit having a calling plug, a pair of telephone lines including a calling and a called station adapted to be connected with said plug, apparatus solely controlled from the calling station adapted to operatively free one of said lines when it is connected to said plug, and automatic switching means effective to place the operatively freeing of said other telephone line under joint control of the calling station and the called station when said other line is connected with said plug.

50 2. In a telephone system having a link circuit provided with a terminal for interchangeable connection with telephone lines, automatic means under the sole control of a calling subscriber to operatively free said telephone line at the end of conversation, another telephone line adapted for connection with said terminal, and automatic means for operatively freeing said other line at the end of conversation, said means controlled by a called subscriber.

55 3. In a telephone system, a link circuit connected to a calling line, a terminal for said link circuit and a called line connected therewith, and relay mechanism automatically and solely controlled over the calling line to operatively free the called line at the end of conversation, another line for con-

nnection to said terminal as a called line, and relay mechanism then automatically and jointly controlled over the calling line and the called line to operatively free the called line at the end of conversation.

70 4. A telephone system including a calling line and a called line and a plurality of switchboard operator's manually operated link circuits for interconnecting said lines, automatic selecting and connecting mechanism between said link circuits and operated to connect them, means applying current to signal the called substation, and relay devices operable over the calling line effective to discontinue said current and to free said calling line from said link circuits and said mechanism, said called line and its associated link circuit remaining connected.

75 5. A telephone system including telephone lines and a link circuit for connecting them, a relay controlling the talking conductors of said circuit, solely controlled from the calling station when said link circuit connects said station in conversational relation with one of said lines, and means automatically operated to place said relay under control of a called station when said link circuit connects the calling station with another of said lines.

80 6. A telephone system including telephone lines and a link circuit for connecting them, a link circuit relay operated when connection is made to a line with a low resistance connection, said relay inoperative when connection is made to a line with a high resistance connection, automatic disconnect apparatus solely controlled over one of a pair of connected lines when said link circuit relay is in one condition, and jointly controlled over the two connected lines when said relay is in the other condition.

85 7. A telephone system including subscribers' lines and an operator's cord circuit for connecting them, a pair of relays for the calling cord operated in parallel over a strand of said cord, and a third relay in the common connection of said relays, said two relays operating when connection is made to any line and said third relay operating when connection is made to certain lines only, automatic disconnect apparatus responsive to the establishment of certain circuit conditions when said third relay is operated and to the establishment of certain other circuit conditions when said third relay is unoperated.

90 110 115 120 125 130 8. A telephone system having telephone lines and a link circuit to interconnect them, a terminal for said circuit for establishing connection directly to a called line, or to a trunk circuit adapted for connection to the called line, a marginal relay operating or remaining inert according to the character of the connections as aforesaid made by said terminal, and automatic disconnect appa-

ratus controlled by said relay and operable by one of a pair of connected lines.

9. A telephone system including telephone lines and a link circuit for connecting them, a relay for said link circuit controlled by the calling subscriber, and a second relay therefor controlled by the called subscriber, means for connecting said link circuit directly to a called line, or to another link circuit for connection to the called line, and automatic disconnect apparatus solely controlled by one of said relays or jointly by them according to which of the connections aforesaid has been made.

15. 10. A telephone system including telephone lines and a link circuit for connecting them, a pair of relays for said link circuit, one controlled by the calling subscriber and the other controlled by the called subscriber, a marginal relay for said link circuit, actuated when connection is made to a low resistance circuit and inert when connection is made to a high resistance circuit, and an electromagnet responsive to open a talking strand of said link circuit, controlled by one of said pair of relays or jointly by the two according to the operative condition of said marginal relay.

11. A telephone system including a calling line and called lines, a link circuit having manually operated connection terminals at each end thereof for interconnecting said calling line and said called lines directly by said link circuit or said link circuit and a trunk circuit in conversational circuit, automatic means for disassociating said link circuit from the called line, controlled solely by the calling subscriber under said link circuit and said trunk circuit conditions and controlled jointly by the calling and called subscribers under said directly connected link circuit conditions.

12. In a telephone system including a calling line and called lines of different classes, a link circuit for interconnecting said calling line with any one of said called lines, automatic means for freeing said calling and called lines from said link circuit although a physical connection remains between said link circuit and said calling and called lines, said automatic means controlled solely over the calling line when connection is made with one class of called lines, and controlled jointly over the calling and called lines when connection is made with the other class of called lines.

13. A telephone system including a calling line, a called local line and a called trunk line, a link circuit having manually operated connection terminals at each end thereof for interconnecting said line and said local or trunk line in conversational circuit, electromagnetic means for said link circuit for freeing said calling line and the called line from said link circuit, said elec-

tromagnetic means controlled solely by the calling subscriber when connection is made with said trunk line, and controlled jointly over the calling and called lines when connection is made with said local line.

14. In a telephone system including telephone lines terminating at a local exchange, and telephone lines terminating at a distant exchange, switchboard operator's manual link circuits for interconnecting said lines at the local exchange or for connecting the local telephone lines with the telephone lines at the distant exchange, automatic disconnect means individual to said link circuit for freeing the calling and called lines from the link circuit connecting them, said means controlled solely over the calling line when said calling line is connected to a called line at the distant exchange, and controlled jointly over the calling and called lines when said calling line is connected to a line at said local exchange.

15. In a telephone system including telephone lines some of which terminate in local jack terminals while others terminate in trunk jack terminals, link circuits for connecting said telephone lines in conversational circuit, automatic link disconnect means individual to said link circuit and controlled solely over the calling line when connection is made with a trunk jack terminal to free the calling and called telephone lines from the link circuit connecting them and controlled jointly over the calling and called lines when connection is made with a local jack terminal.

16. A telephone system including a calling telephone line and called telephone lines, link circuits for interconnecting said calling line with said called lines via said link circuit or said link circuit and a trunk circuit, and automatic means for operatively but not physically disassociating a connected link circuit from the calling and called lines, said means controlled under said link and trunk connection conditions solely over the calling line and under link connected conditions jointly over the calling and called lines.

17. A telephone system including a calling line and called lines, a link circuit having manually operated connection terminals at its opposite ends for interconnecting said calling line and said called lines via said link circuit or said link circuit and a trunk circuit, automatic means for disassociating said link circuit from the called line controlled solely by the calling subscriber during a link and trunk connection, and controlled jointly by the calling and called subscribers during a link circuit connection.

18. A telephone system including subscribers' telephone lines, a link circuit having manually operated connection terminals at the opposite ends thereof for intercon-

necting said lines via said link circuit or
said link circuit and a trunk circuit, electro-
magnetic means for said link circuit for
freeing the called line and the calling line
from said link circuit, said means controlled
solely by the calling subscriber during a
link and trunk connection, and controlled

jointly by a calling and a called subscriber
during a link circuit connection.

Signed by us at Chicago, in the county ¹⁰
of Cook and State of Illinois, this 26 day
of April, 1921.
